(57) **CLAIM**

I claim the ornamental design for a ceiling mount, as shown and described.

DESCRIPTION

FIG. 1 is a perspective view of the ceiling mount showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom view thereof;

FIG. 8 is a perspective view of another embodiment of the ceiling mount showing my new design;

FIG. 9 is a front view of the ceiling mount in FIG. 8;

FIG. 10 is a rear view of the ceiling mount in FIG. 8;

FIG. 11 is a right side view of the ceiling mount in FIG. 8;

FIG. 12 is a left side view of the ceiling mount in FIG. 8;

FIG. 13 is a top plan view of the ceiling mount in FIG. 8; and,

FIG. 14 is a bottom view of the ceiling mount in FIG. 8.

The broken line showing of portions of the ceiling mount in FIGS. 8-14 forms no part of the claimed design.
